(57) **CLAIM**

The ornamental design for a riding trowel having edge guards with safety covers, as shown.

DESCRIPTION

FIG. 1 is a frontal isometric view of our new riding trowel having edge guards with safety covers;

FIG. 2 is a front plan view thereof;

FIG. 3 is a rear isometric view of thereof;

FIG. 4 is a top plan view thereof; and,

FIG. 5 is an enlarged, fragmentary isometric view of a typical rotor.
